UNITED STATES PATENT OFFICE.

SHEPARD J. GOLDBERG, OF NEW YORK, N. Y.

DESIGN FOR A BOTTLE.

46,090.

Specification for Design.

Patented July 14, 1914.

Application filed May 23, 1914. Serial No. 840,630. Term of patent 14 years.

To all whom it may concern.

Be it known that I, SHEPARD J. GOLDBERG, a citizen of the United States, residing at the city of New York, borough of Brooklyn, Kings county, and State of New York, have invented a new, original, and ornamental Design for a Bottle, of which the following is a specification, reference being had to the accompanying drawings, forming part thereof, and in which—

Figure 1 is a side view showing a bottle

made according to, and incorporating my said design; Fig. 2 is a sectional view taken on the line 2—2 of Fig. 1, and Fig. 3 is a top view.

I claim:—

The ornamental design for a bottle as shown.

SHEPARD J. GOLDBERG.
